DESIGN FOR A BALL TOSSING TOY

Abraham M. Baker, Providence, R. I.

Application February 27, 1945, Serial No. 118,158

Term of patent 14 years

(CL. D34—15)

To all whom it may concern:

Be it known that I, Abraham M. Baker, a citizen of the United States, residing at Providence, in the county of Providence and State of Rhode Island, have invented a new, original, and ornamental Design for a Ball Tossing Toy, of which the following is a specification, reference being had to the accompanying drawing, forming a part thereof.

The figure is a perspective view of a ball tossing toy showing my new design.

I claim:

The ornamental design for a ball tossing toy, as shown.

ABRAHAM M. BAKER.
